GAS BURNER

Charles L. Lehman, Edmonton, Alberta, Canada

Application March 9, 1936, Serial No. 67,984
In Canada May 31, 1935

1 Claim. (Cl. 158—106)

The invention relates to a burner construction and more especially to a gas burner.

The primary object of the invention is the provision of a burner, wherein burner orifices are readily and easily accessible so that the same can be conveniently cleaned should they become corroded and without removal of a burner from a furnace, the flame tubes of the burner being of a construction to direct the flame to the walls of the furnace and thereby eliminating the employment of a deflector for the spreading of the flames.

Another object of the invention is the provision of a burner of this character, wherein the parts are of such construction as to assure easy assembly and maintaining a low cost of production and such burner is covered in a manner to shut off the unnecessary air from the center of the furnace and diverting the air to a gas flame, the burner in its entirety being of novel construction and is of the Bunsen principle.

A further object of the invention is the provision of a burner of this character, which is extremely simple in construction, thoroughly reliable and efficient in its operation, durable, readily and easily installed within a furnace and inexpensive to manufacture.

With these and other objects in view, the invention consists in the features of construction, combination and arrangement of parts as will be hereinafter more fully described, illustrated in the accompanying drawing, which discloses the preferred embodiment of the invention and pointed out in the claim hereunto appended.

35 In the accompanying drawing:

Figure 1 is a fragmentary elevation of a burner constructed in accordance with the invention.

Figure 2 is a sectional view on the line 2—2 of Figure 1 looking in the direction of the arrows.

40 Figure 3 is a top plan view.

Figure 4 is an enlarged sectional view on the line 4—4 of Figure 1 looking in the direction of the arrows.

45 Similar reference characters indicate corresponding parts throughout the several views in the drawing.

Referring to the drawing in detail, the burner comprises, in this instance, a pair of upper and lower half circular shaped brackets 10 and 11, respectively, these being disposed in their superposed spaced relation in a horizontal plane and the upper brackets 10, each has an upstanding flange 12 at its outer marginal edge.

50 Removably fitted with these brackets 10 and 11 are the vertical portions of flame tubes 13, these

being spaced perpendicularly uniformly from each other and each has a contracted lower end 14 accommodated in a correspondingly sized opening in the lower bracket 11, the contracted end being for the formation of a seating shoulder 15 for the tube so that it will rest upon the lower bracket 11 when in working position. The tubes 13 have the upper laterally angled burner tips 16 for directing the flame against or toward the wall of a furnace accommodating the burner. 10

5 Tie rods 17 join the brackets 10 and 11 in their superposed relation to each other to provide a unitary supporting frame for the flame tubes.

Beneath each lower bracket 11 is a gas fuel supply pipe 18, it conforming to the shape of said bracket 11 and at its front is joined by a coupling 19 with a source of fuel supply while the rearmost end of such pipe is suitably plugged for the closing thereof. This pipe 18 at its upper side has formed therein burner orifices 20, these confronting the lower open ends of the flame tubes 13 for the jetting of fuel into said tubes.

20 Removably resting on the upper brackets 10 is a plate 21 which shuts off the center air within the furnace and thus closing off the unnecessary air from the center of said furnace and diverting the air to the gas flames. The pipe 18 is uniformly spaced below open lower ends of the flame tubes 13 so as to allow air to follow the jet for proper mixture of air with the fuel for perfect combustion in the operation of the burner, the spacing of the pipe 18 from the lower bracket 11 being had by the leg 22 depending from the lower bracket and seated upon said pipe. The tips 16 of the flame tubes rest in notches 24 in the upstanding flanges 12 of the brackets 10 so that the turning of the flame tubes from their set position when fitting the brackets will be avoided, the tips being extended beyond the flanges 12 for considerable spread of the burner when lighted. These brackets 10 and 11 are held uniformly spaced from each other through the medium of suitable sleeves 23 which surround the rods 17 and constitute the spacers for the said brackets 10 and 11 and the latter are held in a rigid position while the flame tubes 13 are readily removable from these brackets for cleaning by sliding each tube 13 out from the brackets 10 and 11 without removal of the brackets or burner from the furnace. The supply pipe 18 with the perforations 20 in the upper side thereof has those rods 17 at the extreme ends of the brackets 10 and 11, each passed downwardly through the leg 22 next thereto with the lower end of such rod 17 threaded into the supply pipe 18 so that these parts will

be joined in this manner although such parts can be otherwise joined.

By the arrangement of the burner and its construction a deflector is unnecessary for the spreading of the flames when the burner is operated because the tips 16 direct the flames from the tubes 13 straight to the walls of the furnace.

What is claimed is:

A gas burner comprising vertically spaced horizontally arranged substantially half ring-like brackets having vertically aligned openings, flame tubes removably fitting said openings and having laterally angled upper ends and reduced lower ends forming shoulders seated against the lowermost brackets concentrically of the openings therein, means holding the brackets in spaced

relation to each other, a fuel pipe beneath the lowermost brackets and spaced from the lower ends of said flame tubes and having burner orifices opening upwardly in the direction of said flame tubes, upstanding flanges at the outer peripheral edges of the uppermost brackets and having rounded notches forming seats for the laterally angled upper ends of the flame tubes, the said angled upper ends of the tubes being extended beyond the flanges and forming tips, a disk-like plate removably seated on the upper brackets with the tips concentrically thereabout, and fasteners included in said means for detachably holding the fuel pipe in fixed position.
